UNITED STATES PATENT OFFICE.

CAMILLO VERI, OF GARFIELD, NEW JERSEY.

WINDOW.

Application filed October 3, 1923. Serial No. 666,370.

To all whom it may concern:

Be it known that I, CAMILLO VERI, a citizen of Italy (having taken out first United States citizenship papers), and a resident of 5 Garfield, in the county of Bergen and State of New Jersey, have invented a new and Improved Window, of which the following is a full, clear, and exact description.

This invention relates to windows and has 10 for an object to provide an improved window construction wherein the usual appearance is presented while at the same time the parts are so formed as to permit both the upper and lower sashes to be swung inwardly when access to their exterior is desired.

Another object of the invention is to provide a window structure wherein a hinged sash is mounted on sliding sash uprights 20 with means which may be operated manually for swinging either the upper or lower sash inwardly at a point near the sill of the window.

Another object of the invention is to provide a window structure in which the glass panes may be readily applied or removed without tools or without injury to the sash.

An additional object is to provide a window structure wherein the window sashes 25 are held in place by removable strips associated with an aperture filling block whereby access may be secured to the inner surface of the window frame on each side.

In the accompanying drawings—

Figure 1 is a perspective view of part of 30 a wall with the window disclosing an embodiment of the invention applied thereto.

Figure 2 is a longitudinal vertical sectional view through Figure 1, approximately on line 2—2, the same being somewhat on an enlarged scale.

Figure 3 is a front view with certain parts broken away of the window shown in Figure 2.

Figure 4 is a horizontal sectional view 45 through Figure 3; approximately on line 4—4.

Referring to the accompanying drawings by numeral, 1 indicates a wall of any desired kind into which is fitted a window frame 3 adapted to carry the sashes 4 and 5. The frame 3 is made in the usual manner except for the provision of strips 6 and 7 held in place by suitable screws or other removable fastening means 8. Each of the strips 6 covers a removable block 9 which

fills an opening in part of the frame 3 and when the strips are removed and the blocks 9 removed, access may be had to the interior of the frame 1 so as to adjust the 60 weights or for any other desired purpose. The frame 3 is also provided with a special top plate 10 held in place by a hinge structure 11 of any desired kind. The plate 10 is in line with the sash 5 so that when said sash is raised to its highest point it will move the plate 10 back to the dotted position shown in Figure 2. It will be noted that the upper end of the sash 5 when fully raised extends into the frame 3 in order to 70 leave an extra space at the bottom through which the outside sash may be swung when desired. The sash 5 is provided with independent sliding bars 12 and 13 of identical construction. The sliding bar 13 is connected to the swinging section 5' of the sash by suitable hinges 14 while the sliding bar 12 is connected to the swinging section 5' through a spring pressed bolt 15. The sliding bar 12 is provided with a plate 16 hinged 80 at 17, said plate being provided with spurs or lugs 18 and 19, spur 18 being normally positioned as shown in Figure 3.

When it is desired to swing the sash section 5' outwardly as shown in Figure 1, the 85 sash is moved upwardly to the dotted position shown in Figure 3 and the plate 16 swung over until the spur or lug 19 projects into the aperture or depression 20 in the frame 3. The bolt 15 is then retracted and 90 the section 5' swung to an open position. It is desirable to use the plate 16 as just described in order to hold the sliding bar 12 in a lowered position.

It will be noted that the sash cord 21 has 95 one end secured to the sliding bar 12, said cord passing over a suitable pulley 22 and carrying any suitable weight. If the sliding bar was not anchored as just described, the weight would immediately raise the 100 same to an upward position. When the section 5' is in the position shown in Figure 1, the window pane 23 may be cleaned from the outer face without the person leaving the room. In connection 105 with the window pane 23, it will be noted that the same is placed in position through a slot 24 formed in the upper end of the section 5', said section 5' having the vertical bars slotted in such a manner as to 110 merge into the slot 24 so that the edges of the pane 23 will project into the side bars

- of the section 5' while the bottom edge will project into a suitable groove in the lower bar and the top edge fit in the slot 24.
- 5 When it is desired to clean or otherwise operate on the outer face of the upper sash 4, sash 5 is moved to a closed position and the bolt 15 allowed to snap into the aperture 15' whereupon the section is locked to 10 the sliding bar 12. The plate 16 is then swung back to the full line position shown in Figure 3 and the entire sash raised until it assumes the dotted position shown in Figure 2. The upper sash is then lowered 15 until the lower end is slightly above the window sill 25. The plate 16' carried by the sliding bar 12' is then shifted until the pin or spur 19' engages the aperture 20' in the window frame 3. This will lock 20 the sliding bar 12' in position so that the bolt 15" may be retracted and the section 4' swung on it hinges 26, which hinges are connected to the sliding bar 13'. It will be noted that the section 4' of the upper sash 25 swings inwardly at substantially the same point as section 5' so that access may be readily had to the outer surface thereof from the interior of a room and without reaching upwardly as the upper sash is in 30 a lowered position. After the section 4' has been moved back to its former position with the bolt 15" engaging an aperture in the sliding bar 12', plate 16' may be released and moved back to the position shown 35 in Figure 3 with the spur or pin 18' projecting into a suitable aperture in the section 4'.
- When the parts are properly connected together as just described, the respective sashes may be raised and lowered in the usual manner and will present the usual appearance of an ordinary window. The thumb members connected with the respective bolts 15 and 15" and the hinges 14 and 26 may, of course, be seen, but these are comparatively small and, therefore, not objectionable.
- What I claim is:—
- In a window structure, a window frame having a pair of slide-ways and an aperture 50 substantially midway of the window frame extending into one of said slide-ways, a sash comprising a pair of sliding bars fitting into said slide-ways, said sash being formed with a pane receiving sash frame, hinge 55 members for hingedly connecting said sash frame with one of said sliding bars, means acting as a catch for disengageably locking the other of said sliding bars to the opposite edge of said sash frame, a plate hingedly 60 connected to the top of said last mentioned sliding bar and normally overlapping the upper end of said sash frame, said plate having oppositely extending pins, one of said pins normally extending into said sash frame and the other into said aperture in 65 said window frame when the plate is swung away from the sash frame whereby a second catch is provided for the last mentioned bar for preventing independent upward movement thereof whereby said catch may be moved to a disengaged position and said sash frame swung on its hinges without permitting the sliding bar to move upwardly.

CAMILLO VERI.
